UNITED STATES PATENT OFFICE.

FREDERICK W. COLE, OF NEWTON, MASSACHUSETTS, ASSIGNOR OF ONE-HALF TO MOSES G. CRANE, OF SAME PLACE.

NON-INTERFERENCE SIGNAL-BOX.

SPECIFICATION forming part of Letters Patent No. 445,799, dated February 3, 1891.

Application filed May 29, 1890. Serial No. 353,523. (No model.)

To all whom it may concern:

Be it known that I, FREDERICK W. COLE, of Newton, county of Middlesex, State of Massachusetts, have invented an Improvement in Non-Interference Signal-Boxes, of which the following description, in connection with the accompanying drawings, is a specification, like letters and figures on the drawings representing like parts.

10 This invention has for its object to construct a non-interference fire-alarm box.

In accordance with this invention a signaling-train of any usual or suitable construction is employed, together with a suitable locking 15 or other controlling lever for it which is operated by a pull or other actuator, which latter may be formed as an independent part or connected to the locking or other controlling lever. The non-interference magnet is preferably included in the signaling circuit, and means are provided for varying the power of 20 said magnet—as, for instance, decreasing its attractive power when the box-door is open.

This invention is herein represented as applied to a normally-wound-up train. The locking-lever for the train is normally held in its locking position by means of a spring, and the pull is made independent of the locking-lever and adapted to raise it against the 25 tension of said spring, or to move it into suitable position to enable it to be again or further moved to release the train. A box-controller is provided which is designed to co-operate with the said locking-lever to control 30 the effective transmission of the signal, said box-controller being governed by the armature of said non-interference magnet.

Figure 1 shows in front elevation a signal-box embodying this invention; Fig. 2, a horizontal section of the box shown in Fig. 1, taken on the dotted line xx ; Fig. 3, a detail of the means shown in Fig. 1 for varying the power of the non-interference magnet; Fig. 4, a rear end view of the switch controlled by 45 the box-door for varying the power of the non-interference magnet; Fig. 5, a front view of the box, showing the door open; Figs. 6, 7, 8, 9, and 10, details of some of the parts shown in Fig. 1 to be referred to; Fig. 11, a detail of 50 a modification to be referred to; Fig. 12, a detail of another modification to be referred

to; Figs. 13 and 14, details of another modification to be referred to.

Referring to Figs. 1 to 10, the main frame-work a supports a signaling-train of any usual or suitable construction, it being herein represented as a normally-wound-up train comprising a drive-wheel a' , engaging a pinion a^2 on a shaft a^3 , which carries a toothed wheel a^4 , which engages a pinion a^5 on a shaft a^6 , 55 which carries a toothed wheel a^7 , engaging a pinion a^8 on a shaft a^9 , carrying the escape-wheel a^{10} , which co-operates with a pallet a^{12} .

The signal-wheel b is herein represented as placed on the shaft a^6 .

Two pens 2 3 are herein represented as bearing on the signal-wheel b , to which the line-wires lead.

The controlling-lever for the box is herein represented as a locking-lever c , secured to a 70 rod or shaft c' , having a pivotal bearing at one end in the front plate and having a loose bearing in an elongated opening in the rear plate. (See Figs. 8 and 9.) A spring c^2 is provided for holding the locking-lever c in its 75 locking position.

The locking-lever c has on its front and lower side a projection c^3 , having an inclined face, and a projection c^4 is secured to the rear side of the toothed wheel a^4 , which co-operates with the projection c^3 , acting to hold the 80 said locking-lever in its locking position in connection with the spring c^2 . The outer end of the locking-lever c has on it a projection c^5 , which when in locking position engages a pin c^6 on the escape-wheel a^{10} .

The pull, which is herein shown as made independent of the locking-lever and represented at d , is pivoted to the frame-work at d' , the rear end of which passes beneath the 90 locking-lever c , so that by depressing said pull d the locking-lever c is raised against the tension of the spring c^2 . When the pull d is depressed, the locking-lever c is lifted, so that the projection c^3 passes above the upper surface of the projection c^4 , as represented by dotted lines, Figs. 6 and 7, but not sufficiently far to enable the projection c^5 to pass over the pin c^6 . As soon as the locking-lever is 95 thus raised the spring c^2 , which acts to depress the said locking-lever, also acts to swerve it toward the wheel a^4 , as represented

by dotted line, Fig. 8, the locking-lever moving in its elongated bearing, especially shown in Figs. 8 and 9. The pin c^6 is made quite short, so that when the lever is thus swung 5 in a horizontal plane the projection c^5 will pass by the end of said pin c^6 and release the train, as represented in dotted lines, Fig. 8. The locking-lever c thus operated, the train will run and the lever c occupy a position 10 against or adjacent to the rear face of the wheel a^4 , with the projection c^3 in the path of movement of the projection c^4 , and as soon as the wheel a^4 makes a complete revolution the projection c^4 will strike against the inclined face of the projection c^3 and move the lever c back in a horizontal plane, so that the projection c^5 will catch the pin c^6 when the escape-wheel completes its rotation.

The non-interference magnet n is herein 20 represented as included in the signal-circuit, its armature n' being secured to or carried by an armature-carrying lever n^2 , pivoted at n^3 and having attached to it a retractile spring n^4 . This armature-carrying lever 25 constitutes the box-controller. The lower end of the box-controller n^2 is beveled, as at n^5 , at one end, (see Fig. 10,) and said armature-carrying lever n^2 terminates adjacent to the end of the locking-lever c . When 30 the locking-lever c is in its locking position and the magnet n demagnetized, the box-controller n^2 will be moved toward the end of the locking-lever c , as represented by dotted and full lines, Fig. 7, so that the said 35 end of the locking-lever will occupy a position contiguous to the beveled portion of the said box-controller. If the locking-lever c is raised when the box-controller n^2 is in this position, the said lever will strike the beveled side n^5 of said box-controller n^2 and will 40 be moved by it a very short distance toward the escape-wheel a^{10} , the elongated bearing for the shaft c' permitting such movement. This box-controller when in this position effectually prevents movement of the locking-lever c toward the wheel a^4 , and hence prevents the release of the train. When the 45 pull is released, the locking-lever c will resume its normal position. This slight movement toward the wheel a^{10} is given for the purpose of compensating for any lost motion that there may be between the parts, the effect of which will be apparent in the co-operation of the projections c^3 c^4 .

As herein shown, (see Fig. 3,) the non-interference magnet has two coils n n^6 , one of which is included in the signaling-circuit and the other in a branch wire 4, and a switch is provided for closing said branch wire 4, the 50 members of which 5 6 are suitably supported on a block, and one of which members is moved into engagement with the other by a plug o , controlled by the box-door. Another switch is provided, represented by the members 5 and 7, which are also controlled by the 55 said plug o , the member 7 of said switch being connected with a branch wire 8, which is

joined to the line-circuit between the coils n n^6 of the non-interference magnet. When the box-door is closed the circuit passes from 70 the line through the pen 2, signal-wheel b , pen 3, wire 9, coil n , coil n^6 , wire 4, switch 6 7, which will at that time be closed, and to the line. When the box-door is open, the current will pass over the pen 2, signal-wheel b , pen 3, 75 wire 9, coil n , branch wire 8, switch 7 5 to the line, thus passing by and shunting the coil n^6 . When the door is thus open, the power of the non-interference magnet is reduced about 80 one-third in view of the fact of the coil n^6 being cut out; but there is presumed to be attractive force enough by the coil n to hold the armature n' against its poles; but if said armature is once retracted there is not sufficient power to draw it up again. Thus it will 85 be seen that the power of the non-interference magnet is controlled by a switch, which is in turn controlled by the box-door. This is for the purpose of preventing the armature responding to the successive impulses from another box when the home-box door is open. Various ways may be devised of accomplishing this same end—viz., to decrease the power 90 of the non-interference magnet when the box-door is open—and I will now proceed to describe several modifications, although I do not desire to limit my invention to the specific arrangements shown for accomplishing this result.

Referring to Fig. 11, the coils n n^6 are connected in circuit substantially the same as in Fig. 3. The coil n^6 , instead of being included in a branch wire, is connected to a shunt-circuit closer 12 13, which, when the door is open, is closed and shunts out the coil n^6 . In 105 this figure I have also represented the armature as carrying the interposed block which is described in United States Patent No. 323,218, dated January 6, 1880.

Referring to Fig. 12, the coils of the non-interference magnets are both included in the signaling-circuit, and a resistance-coil p is connected in a branch wire with a circuit-closer p' , and when the door is open the said circuit-closer p' is closed, so that the current 115 will divide, part going through the non-interference magnet and part through the resistance-coil, thereby reducing the strength of the magnet. In this figure the armature is arranged to co-operate with a locking-lever, 120 substantially as shown in United States Patent No. 165,918, dated July 27, 1875.

In Figs. 13 and 14 the coils n n^6 of the non-interference magnet are included in the signaling-circuit, and an auxiliary armature t is 125 pivoted at t' , which is adapted to co-operate with the sides of the cores of the coils. Said armature is moved positively by the plug o on the door, so that when the door is open the armature will be drawn against the cores by 130 means of the spring t^2 , and will thereby absorb a portion of the magnetism and reduce its pull on the armature n' .

As above stated, I have described in con-

nection with Figs. 11 and 12 other forms of controlling devices for signal-boxes. So I do not desire to limit my invention as regards the variation of the power of the non-interference magnet to any particular form of a signal-box.

I claim—

1. In a signal-box, the combination, substantially as described, of a signaling-train, a non-interference magnet, its armature, a box-controller governed thereby, and means controlled by the box-door for slightly decreasing the power of said non-interference magnet when said door is open, that it may hold but not attract its armature, substantially as described.
2. In a signal-box, a signaling-train, a non-interference magnet, its armature, and a box-controller governed by the said armature, and a switch connected electrically with one of the coils of said non-interference magnet, which is adapted to disable or render inoperative said coil, substantially as described.
3. In a signal-box, a signaling-train, a non-interference magnet, its armature and box-controller governed by the said armature, and a switch connected electrically with one of the coils of said non-interference magnet, which is adapted to disable or render inoperative said coil, said switch being controlled by the box-door, substantially as described.
4. In a signal-box, a signaling-train, a non-interference magnet comprising two coils n^6 , its armature and armature-carrying lever, and two switches controlled by the box-door, one for including one of the coils in the signaling circuit and the other for including both coils in the signaling-circuit, substantially as described.
5. In a signal-box, a signaling-train, a locking-lever therefor, and means for moving it

against the tension of its holding-spring, combined with a projection c^3 on said locking-lever, and a projection c^4 on one of the wheels 45 of the train, and a projection c^5 on said locking-lever, and pin on one of the wheels of the train engaged by said projection, substantially as described.

6. In a signal-box, a non-interference magnet, its armature, and a signaling-train, a vertically and horizontally movable locking-lever therefor, combined with projections carried by moving parts of the train, with which said locking-lever co-operates, substantially 55 as described.

7. In a signal-box, a signaling-train, a locking-lever, means for holding it in its locking position, and two actuators for said locking-lever, one for placing it in condition to operate and the other to move it to release the train, combined with a box-controller, non-interference magnet, and its armature, substantially as described.

8. In a signal-box, a signaling-train, a locking-lever for it, and a non-interference magnet and its armature, combined with a projection on one of the wheels of the train for holding the locking-lever in its locking position when at rest, and a box-controller governed by the armature of said non-interference magnet for also holding the locking-lever in its locking position when disengaged from said projection and when the armature is retracted, substantially as described.

In testimony whereof I have signed my name to this specification in the presence of two subscribing witnesses.

FREDERICK W. COLE.
